DESIGN FOR A BOWLING ALLEY SERVICE UNIT OR SIMILAR ARTICLE

Andrew L. Henkel and Burke M. Ewing, Chicago, Ill., assignors to The Brunswick-Balke-Collender Company, Chicago, Ill., a corporation of Delaware

Application April 10, 1940, Serial No. 91,579

Term of patent 14 years

To all whom it may concern:

Be it known that we, Andrew L. Henkel and Burke M. Ewing, both citizens of the United States and both residing in the city of Chicago, in the county of Cook, State of Illinois, have jointly invented a new, original, and ornamental Design for a Bowling Alley Service Unit or Similar Article, of which the following is a specification, reference being had to the accompanying drawing, forming a part thereof.

Figure 1 is a side elevational view of a bowling alley service unit or similar article showing our new design;

Figure 2 is a top plan view thereof;
Figure 3 is a front elevational view thereof.
The rear of the device is plain and the opposite side is similar to that shown.

We claim:
The ornamental design for a bowling alley service unit or similar article, as shown and described.

ANDREW L. HENKEL.
BURKE M. EWING.
